UNITED STATES PATENT OFFICE.

ARTHUR R. BUSH, OF BOSTON, MASSACHUSETTS, ASSIGNOR TO PAINE & FRANCIS, OF SAME PLACE.

SWITCH.

SPECIFICATION forming part of Letters Patent No. 425,205, dated April 8, 1890.

Application filed June 11, 1889. Serial No. 313,836. (No model.)

To all whom it may concern:

Be it known that I, ARTHUR R. BUSH, of Boston, county of Suffolk, State of Massachusetts, have invented an Improvement in 5 Pocket-Switches, of which the following description, in connection with the accompanying drawings, is a specification, like letters on the drawings representing like parts.

This invention has for its object to provide 10 a novel switch, as will be described, especially adapted to be used on incandescent-electric-light circuits.

In accordance with my invention, a disk or plate has secured to or forming part of it on 15 one side thereof two arms or projections, preferably of wood or other insulating material, and separated from each other, preferably, a considerable distance. The arms or projections referred to have secured to them contact arms or strips, preferably bent to present 20 an inclined surface, with which co-operates a contact member, herein shown as a metal plate or strip secured to a block, preferably of wood or other insulating material, fastened 25 in suitable manner to a spindle extended through the disk. The spindle referred to extends, as herein shown, through a sleeve secured to or forming part of the disk on its side opposite to that to which the arms or 30 projections are secured, and the said sleeve is provided with a radial hole or opening, through which is extended a bar or rod, preferably made beveled at its end to engage, preferably, a notch in the spindle (but which 35 may be a projection of any sort, as will be described) and lock the said spindle against upward or outward movement when the said spindle is pressed upon to bring the contact member secured to it in contact with the strips or 40 arms to complete the electric circuit. The rod referred to constitutes a retaining or locking device and is secured to or forms part of a releasing device, herein shown as a yoke to which is secured a finger-piece, and by 45 pressing which the retaining device may be disengaged from the notch of the spindle when it is desired to open the circuit. The retaining device is normally kept pressed against

the spindle, preferably by a spiral spring which encircles it. The spindle and its attached contact member are moved upward or outward when disengaged from the retaining device, preferably by a spring. The disk and the retaining and releasing devices are preferably concealed or covered by a suitable cap 55 having a hole, through which the upper end of the spindle projects, and provided with a suitable opening at its side, through which the finger-piece of the releasing device is extended. The disk will preferably be secured 60 to a shell or casing of tin or other suitable material, which is adapted to be inserted into a hole or pocket in the wall of a building or room, so that when in position the switch is covered by the cap, the remaining parts being 65 concealed.

The particular features in which my invention consists will be pointed out in the claims at the end of this specification.

Figure 1 is a vertical section of a switch embodying my invention; Fig. 2, a top or plan view of the switch shown in Fig. 1, with the cap or cover and thumb-nut removed; and Fig. 3, a modification to be referred to.

The base *a*, preferably made as a metal disk, 75 has secured to or forming a part of it at one side thereof arms or projections *a'* *a''*, which may be of wood or other suitable material. The arms *a'* *a''* have secured to them contact plates or strips *a³* *a⁴*, having their ends bent, 80 as at *a⁵*, to present inclined surfaces with which co-operates a contact member *a⁶*, preferably made as a plate or strip, secured, as shown, to a block *a⁷*, of wood or other insulating material, on a spindle *a⁸*, extended through 85 the disk *a* and through a sleeve *b*, secured to or forming part of said disk. The spindle *a⁸* is provided with a notch *b'*, which is adapted to receive the preferably beveled end of a rod *b²*, provided, as shown, with screw-threads 90 *b³*, to engage the threaded opening of a yoke *b⁴*, having detachably secured to its opposite end, as by screw-threads, a finger-piece *b⁵*. The rod *b²* has its outer end inserted into an opening in a lug *b⁶*, against which presses one 95 end of a spiral spring *b⁷*, encircling the said

rod, and having its other end acting against the yoke b^4 , the said spring normally acting to force the rod b^2 forward, so that its end will engage the notch b' of the spindle when the latter is depressed to bring the contact member a^6 in contact with the contact-arms $a^3 a^4$, the said rod b^2 constituting a retaining or locking device for the said spindle.

The sleeve b is provided with a longitudinal slot, (see dotted lines, Fig. 1,) into which a rod c , or it might be a projection on the spindle, is adapted to pass when the spindle is depressed.

The spindle a^8 is moved into its outward position when the retaining device is withdrawn from the notch b' , preferably by a spiral spring c' , encircling the sleeve b , one end of the said spring acting against a shoulder c^2 on the said sleeve and the other end against a washer or ring c^3 , encircling the sleeve b , and kept pressed against the rod or projection c by the said spring.

The disk in practice will preferably be inserted into a case or shell d , fitted into a hole or pocket in the wall of the building, and the parts of the switch on the outer face of the disk a will be concealed by a suitable cap or cover d' , which may be nickel-plated or otherwise ornamented to give a pleasing appearance to the switch and through which the upper end of the spindle a^8 is extended, it being provided outside the cap with a suitable thumb-nut d^2 . The cap d' is provided at one side with a suitable opening, through which the finger-piece b^5 extends.

It will thus be seen that when the switch is placed in operative position the parts are concealed within the cap, leaving only the thumb-nut d^2 and the finger-piece b^5 accessible to the operator.

The line-wires are secured to the contact-arms $a^3 a^4$ by suitable screws $d^4 d^5$.

As shown in Fig. 1 the switch is closed, the circuit being completed, as will be readily understood, through the contact-arms $a^3 a^4$ and contact member a^6 , and if it is desired to break the circuit the operator presses upon the finger-piece b^5 , which forces the yoke b^4 and the rod b^2 , attached thereto, in the direction of the arrow 20, thereby withdrawing the end of the said rod from the notch b' in the spindle a^8 , leaving the latter free to be moved upward by the spiral spring c' , thus removing the member a^6 from contact with the arms $a^3 a^4$.

My improved switch, being designed to be inserted into a hole or pocket in a wall of the building, is designated by me as a "pocket-switch."

I have herein shown a single-pole switch; but I do not desire to limit my invention in this respect, as a double or other multiple pole switch may be constructed in similar manner—as, for instance, two or more independent sets of contact-arms $a^3 a^4$ may be se-

cured to the projections a' a^2 , and two or more independently co-operating contact members a^6 may be secured to the block a^7 , all the contact members being moved with the spindle a^8 .

I have herein shown the spindle as provided with a notch to be engaged by the retaining device; but I do not desire to limit myself to this construction, as it is evident the said spindle may be provided with a collar or other projection f , as shown in Fig. 3, with which the retaining device co-operates.

It will be noticed that when the contact member a^6 is withdrawn from engagement with the contact-arms $a^3 a^4$ to open the circuit 80 an air-space exists between each contact-arm $a^3 a^4$ and the contact member a^6 , thus forming a double air-space or break for the switch, thereby making the best possible break in the circuit, and at the same time reducing the arc 85 when the circuit is opened.

I claim—

1. In a pocket-switch, the combination, with a base provided with projecting arms a' a^2 , having contact-pieces $a^3 a^4$ secured thereto 90 and bent to present inclined surfaces, of a co-operating contact member consisting of a strip or plate a^6 , a spindle extended through the said base and to which the contact member a^6 is attached, a spring to move said spindle, a retaining device consisting of a rod b^2 , a spring to move said rod into engagement with said spindle, a yoke secured to said rod and having a finger-piece, and an independent cap covering said yoke and rod, and having 95 openings through which the spindle and finger-piece are extended, substantially as described.

2. In a pocket-switch, the combination, with a metallic base provided with projecting 105 arms of insulating material and contact-pieces $a^3 a^4$ secured thereto, of a co-operating contact member consisting of a block of insulating material and a metal plate secured to said block, a spindle secured to said block and extended through the said base, a spring to move said spindle, a retaining device consisting of a rod b^2 , a spring to move said rod into engagement with said spindle, a yoke secured to said rod and having a finger-piece, and an 110 independent cap covering said yoke and rod, and having openings through which the spindle and finger-piece are extended, substantially as described.

3. In a pocket-switch, the combination, with 115 a case or shell, of a base provided with arms a' a^2 , extended into said case or shell, and having contact-pieces $a^3 a^4$ secured thereto and bent to present inclined surfaces, of a co-operating contact member consisting of a strip 120 or plate a^6 , a spindle extended through the said base and to which the contact member a^6 is attached, a spring to move said spindle, a retaining device consisting of a rod b^2 , a spring to move said rod into engagement with 125

70.

said spindle, a yoke secured to said rod and having a finger-piece, and an independent cap covering said yoke and rod, and having openings through which the spindle and finger-piece are extended, substantially as described.

In testimony whereof I have signed my

name to this specification in the presence of two subscribing witnesses.

ARTHUR R. BUSH.
